UNITED STATES PATENT OFFICE

2,449,386

DOOR AND CLOSURE HOLDER

Francis Johnson, Detroit, Mich.

Application June 28, 1944, Serial No. 542,468

11 Claims. (Cl. 292—74)

1

The present invention relates to improvements in closure holders, and more particularly, to a closure holder of the friction type.

The primary object of the invention is to provide a closure holder which is adapted to retain a door or other closure in its open position which may be easily assembled and installed without materially altering the structure of the door or frame therefor.

Another object of the invention is to provide a closure holder constructed and designed to enhance its utility and application to swinging closures of various types as well as closures which are differently hung.

Another object of the invention is to provide a closure holder including a yieldingly urged shoe member for engaging a portion of the door edge or closure so as to frictionally engage the same and retain the door in its open position.

Another object of the invention is to provide a closure holder of the above-mentioned character which is simple in construction, comprised of comparatively few parts to become out of order and easily installed in position.

Other objects and advantages of the invention will become apparent during the course of the following description of the accompanying drawing, wherein:

Figure 1 is a front elevational view of the closure holder illustrating the construction of the supporting bracket and the manner in which the yieldingly urged shoe member is supported therefrom;

Figure 2 is a top plan view of a closure holder showing the general shape and design of the shoe member to permit a wide number of applications and installations;

Figure 3 is a transverse cross sectional view of the closure holder illustrating in detail the various features of construction and further showing the manner in which the shoe member is yieldingly supported and spring tensioned;

Figure 4 is a plan view of the closure holder illustrating the same in position on the door jamb directly above the top edge of a door so that the yieldingly mounted shoe member will engage the surface thereof and hold the door in a partly opened position;

Figure 5 is a front elevational view of the closure holder illustrating the manner in which the same is positioned with respect to a door frame and closure member therefor similar to Figure 4;

Figure 6 is a top plan view similar to Figure 4 showing the closure holder in a slightly different

2

position to retain the closure or door in its fully opened position;

Figure 7 is a top plan view of a modified form of the invention showing a slightly differently constructed shoe member for yieldingly engaging the top of the door; and

Figure 8 is a vertical cross-sectional view of another slightly modified form of the invention showing a bracket structure of increased size.

In the form of the invention shown in Figures 1 to 6 inclusive, the reference character 5 will generally be employed to designate a bracket member for being mounted above a swinging closure D in either of the two positions shown in Figures 4, 5 and 6. As usual, the door D is hung by means of suitable hinges H in the opening O of the door frame F.

The bracket member 5 comprises a rear wall 6 having spaced apertures 7 for receiving fastening screws or the like and connecting the rear wall 6 is a pair of side walls 8 having inwardly directed flanges 9 at the lower end thereof. The flanges 9 are integrated with an inwardly extending flange 10 formed on the rear wall 6 at the lower portion thereof, thereby completing the bracket structure. The side walls 8 are triangular in shape as illustrated in Figure 3 to provide a finished appearance and the edges of the bracket are slightly rounded.

Supported on the inwardly extending flanges 9 and 10 is a friction shoe member generally designated by the reference character 11 and said shoe member is of cruciform shape and includes a longitudinal bar portion 12 arcuately curved throughout its length and terminating at the ends in straight portions 13 parallel with the flanges 9. Oppositely disposed laterally extending wing portions 14 and 15 are formed on the shoe member 11 intermediate the ends of the longitudinal bar portion 12 and the forwardly projecting wing portion 14 is arcuately curved upwardly to provide a rounded surface portion 16 curved in a plane similar to the plane of the curvature of the bar 12. The rear wing portion 15 is slightly bent as at 18 and offset as at 19 so that said wing portion 15 may extend above the inwardly directed flange 10 of the rear wall 6.

The free end portions 13 and 15 of the friction shoe member 11 are provided with suitable apertures 20 and 21 respectively for receiving vertically disposed bolts 22 and 23 respectively which have their lower ends provided with suitable head portions 24 and 25. The bolts 22 and 23 are passed through openings 26 and 27 in the inwardly extending flanges 9 and 10 respectively

and project upwardly through the openings 20 and 21 in the ends of the shoe member 11 so as to guide the shoe member in its vertical movement. Coil springs 28 are mounted on the bolts 22 and 23 with their lower ends in engagement with the parallel portions 13 and 15 of the friction shoe member 11 and their upper ends in engagement with a washer 29 held in place by nuts or the like 30 threaded on the upper screw-threaded ends of the bolts 22 and 23.

Interposed between the inwardly extending flanges 9 and 10 and the respective free ends 13 and 15 of the friction shoe member 11 is a series of spacing washers 31 for adjusting the height of the friction shoe 11 with respect to the bracket 5, to thereby facilitate the adjustment of the shoe with respect to the top edge of the closure member or door and eliminate the exact positioning of the bracket 5 from the door jamb or frame F. By tightening or loosening the nuts 30 on their bolts 22 and 23, the tension of the springs 28 will be increased or decreased so that the friction shoe 11 may be placed under spring tensions of different degrees.

When the closure member is mounted as shown in Figures 4 and 5 such as for holding the door or closure D in a partly opened position, the bracket 5 is secured in place by screws or the like 32 being passed through the apertures 7 so as to position the bracket 5 directly above the hinge H of the closure. In this position, the closure or door D will have its top edge engaged by the arcuately curved bar portion 12 of the friction shoe 11, thereby frictionally holding the door D in its partly opened position.

When it is desired to mount the door closure so as to retain the door or closure D in its fully opened position, the bracket 5 is secured to the door jamb or frame F by screws 32 being passed through the apertures 7 as shown in Figure 6. In this position, the bracket 5 is slightly offset from the vertical axis of the hinge 8 so that when the door D is opened, the top edge thereof will be engaged by the wing portion 14 of the friction shoe and will slide therebeneath under the curved surface 16 thereof. As the door D is moved to its open position, the sliding shoe 11 will be elevated, against the tension of the coil spring 28 so that the shoe will be yieldingly urged into engagement with said closure against the top edge thereof and retain the same in its fully opened position.

When the door holder is used for closures hung for double swinging movement, it is mounted in the position shown in Figures 4 and 5 on either side of the door frame F, so as to engage the top edge of the door when the same is swung inwardly or outwardly. In the double hung type closure, a door stop as shown in Figures 1 to 3 may be mounted on both sides of the door frame F so as to function as above described.

In the modified form of the invention shown in Figure 7, the bracket 5 is identical in construction and includes a rear wall 6, side walls 8 having the integrated flanges 9 and 10. The friction shoe 11a is slightly different in construction and comprises a bar portion 12a which is arcuately curved longitudinally and has its ends supported on bolts 22a similar to the form of the invention shown in Figures 1 to 6 inclusive. Nuts 30a are threaded on the upper ends of the bolts 22a to hold the friction shoe 11a in position on top of suitable coil springs mounted in identically the same manner as shown in Figures 1 to 6. When the bracket 5 shown in Figure 7 is mounted on a

door jamb in a similar fashion, the top edge of the door engages the arcuately curved surface of the bar portion 12a in the same manner as pointed out in connection with Figures 4 and 5.

5 In the other modified form of the invention shown in Figure 8, the bracket 5a is shaped similar to the bracket 5 and includes a rear wall portion 6a having connected thereto at each end thereof a side wall portion 8a which is triangular in shape and is formed slightly greater in length than the side walls 8 of the bracket 5 in Figures 1 to 7 inclusive.

Formed integral with the rear wall and side walls 5a and 8a are inwardly directed flanges 9a and 10a and said rear and side walls are suitably apertured for receiving screws or the like to facilitate fastening of the bracket to a door jamb or frame directly above the hinges supporting the closure member for said door frame or jamb.

20 The friction shoe 11a is of cruciform shape and includes an elongated bar 12a identical in shape to the bar 12 in Figures 1 to 6 and said bar is provided with a forwardly projecting wing portion 14a curved in a direction transverse to the longitudinal bore 12a. Similarly, a wing 15a is formed on the bar 12a in opposed relation to the wing 14a and said wing is curved in a direction transversely of the bar 12a for a portion of its length as 30 at 18a and terminates in a flat parallel end portion 17a disposed above the rear wall flange 10a.

Bolts 22a and 23a are passed through openings in the flanges 9a and 10a respectively, and extend through suitable apertures in the ends of 35 the longitudinal bar 12a and rearwardly extending wing portions 15a. Coil springs 28a are mounted on the bolts 22a and 23a and are held in place by nuts 30a similar to the form of the invention shown in Figures 1 to 6 inclusive.

40 Interposed between the inwardly extending flanges 9a and 10a and the ends of the elongated bar 12a and wing extension 15a is a series of spacing washers 31a to properly position the friction shoe 12a with respect to the upper edge of 45 a door or closure, so as to place said friction shoe under a predetermined tension. The structure shown in the modified form of the invention is identical with that shown in Figures 1 to 6 inclusive except that the side wall portions 8a are 50 slightly longer and the arcuate curvature of the rearwardly extending wing portion 15a is moderated to provide a closure retainer and stop applicable to closures which are double hung and capable of swinging movement in two directions 55 as well as closures which are hinged for singly swinging movement.

With a structure of this type, the top edge of the door or closure will be engaged at a point spaced further from the axis of the closure hinge and thereby give a better gripping action on the top edge of the door or closure.

It is to be understood that the forms of the invention herewith shown and described are to be taken as preferred embodiments of the same and that various changes may be made in the shape, size and arrangement of parts without departing from the spirit of the invention or the scope of the subjoined claims.

What I claim is:

70 1. A closure holder, comprising an approximately U-shaped bracket adapted to be affixed to a door frame, an elongated arcuately curved shoe member carried at its ends by the bracket arms and having its arcuately-curved intermediate portion extending through the gap between

said arms adapted to engage the top edge of said closure adjacent the hinged end thereof, guide members carried by the bracket arms for slidably supporting each end of said shoe member, and resilient elements mounted on said arms for yieldingly urging said shoe member into frictional engagement with said closure, said resilient elements being mounted on the guide members and arranged to exert a downward pressure on each end of said shoe member.

2. A closure holder, comprising a bracket adapted to be affixed to a door frame, a shoe member carried by the bracket adapted to engage the top edge of said closure adjacent the hinged end thereof, guide members carried by the bracket for said shoe member, and resilient elements for yieldingly urging said shoe member into frictional engagement with said closure, said shoe member being of a cruciform shape and consisting of a bar member having forwardly and rearwardly extending wing portions.

3. A closure holder, comprising a bracket adapted to be affixed to a door frame, a shoe member carried by the bracket adapted to engage the top edge of said closure adjacent the hinged end thereof, guide members carried by the bracket for said shoe member, and resilient elements for yieldingly urging said shoe member into frictional engagement with said closure, said shoe member being of a cruciform shape and consisting of a bar member having forwardly and rearwardly extending wing portions, and said bar member and wing projections being arcuately curved from the central portion of the shoe member to the ends thereof.

4. A closure holder adapted to be positioned above a swinging closure adjacent the hinged edge thereof, comprising a bracket for being affixed to the closure frame, said bracket being provided with interconnected rear and side walls having integrated inwardly extending flanges, guide members supported on the flanges, a friction shoe slidably supported on said guide members adapted to engage the top edge of said closure adjacent the hinged edge thereof, and yielding spring elements carried by said guide members for placing said shoe member under tension to urge the same into frictional contactual engagement with said closure.

5. A closure holder adapted to be positioned above a swinging closure adjacent the hinged edge thereof, comprising a bracket for being affixed to the closure frame, said bracket being provided with interconnected rear and side walls having integrated inwardly extending flanges, guide members supported on the flanges, a friction shoe slidably supported on said guide members adapted to engage the top edge of said closure adjacent the hinged edge thereof, and yielding spring elements carried by said guide members for placing said shoe member under tension to urge the same into frictional contactual engagement with said closure, said shoe member being of cruciform shape and being curved in the same spherical plane.

6. A closure holder adapted to be positioned above a swinging closure adjacent the hinged edge thereof, comprising a bracket for being affixed to the closure frame, said bracket being provided with interconnected rear and side walls having integrated inwardly extending flanges, guide members supported on the flange, a friction shoe slidably supported on said guide members adapted to engage the top edge of said closure adjacent the hinged edge thereof, and yielding spring ele-

ments carried by said guide members for placing said shoe member under tension to urge the same into frictional contactual engagement with said closure, said friction shoe member consisting of an arcuately curved bar having an intermediate forwardly extending wing portion curved in a direction at right angles to the curvature of said arcuately curved bar member.

7. A closure retainer for hinged closures, comprising an approximately U-shaped bracket with vertically-extending walls at the side and rear edges thereof adapted to be affixed to the frame of the closure above the hinge therefor, guide members carried by said bracket arms for a friction shoe having its ends engaging said guide members and an arcuate intermediate portion extending through the gap between said arms for frictional contactual engagement with said closure at the top edge thereof, and coil springs associated with said guide members and yieldingly urging the arcuate portion of said shoe member through said gap into frictional contact with the closure for holding said closure in an open position.

25 8. A closure holder for swinging hinged closures supported in a closure frame, comprising a bracket adapted to be affixed to said frame above and adjacent the hinged edge of said closure, said bracket being formed with a rear wall connecting vertical side walls having inwardly directed flanges, guide bolts extending upwardly through said flanges, an arcuately curved friction shoe having its ends supported on a pair of said guide bolts, wing extensions formed on said arcuately curved shoe member intermediate the ends thereof, one of said wing extensions being slidably guided on the guide bolt carried by the flange on the rear wall of said bracket, and coil springs mounted on said guide bolts for placing said arcuately curved shoe member under tension.

40 9. A closure holder for swinging hinged closures supported in a closure frame, comprising a bracket adapted to be affixed to said frame above and adjacent the hinged edge of said closure, said bracket being formed with a rear wall connecting vertical side walls having inwardly directed flanges, guide bolts extending upwardly through said flanges, an elongated arcuately curved friction shoe having its ends supported on a pair of said guide bolts, wing extensions formed on said arcuately curved shoe member intermediate the ends thereof, one of said wing extensions being slidably guided on the guide bolt carried by the flange on the rear wall of said bracket, coil springs mounted on said guide bolts for placing said arcuately curved shoe member under compression, and adjusting nuts threaded on said bolts for varying said compression.

60 10. A closure holder for swinging hinged closures supported in a closure frame, comprising a bracket adapted to be affixed to said frame above and adjacent the hinged edge of said closure, said bracket being formed with a rear wall connecting vertical side walls having inwardly directed flanges, guide bolts extending upwardly through said flanges, an elongated arcuately curved friction shoe having its ends supported on a pair of said guide bolts, wing extensions formed on said arcuately curved shoe member intermediate the ends thereof, one of said wing extensions being slidably guided on the guide bolt carried by the flange on the rear wall of said bracket, coil springs mounted on said guide bolts for placing said arcuately curved shoe member under compression, adjusting nuts threaded on

said bolts for varying said compression, and spacing washers interposed between said flanges and the ends of said arcuately curved shoe member as well as said one extension to permit adjustment of said shoe member to compensate for wear between the shoe member and upper edge of said closure.

11. A closure holder for swinging hinged closures supported in a closure frame, comprising a bracket adapted to be affixed to said frame above and adjacent the hinged edge of said closure, said bracket being formed with a rear wall connecting vertical side walls having inwardly directed flanges, guide bolts extending upwardly through said flanges, an arcuately curved friction shoe having its ends supported on a pair of said guide bolts, wing extensions formed on said arcuately curved shoe member intermediate the ends thereof, one of said wing extensions being slidably guided on the guide bolt carried by the flange on the rear wall of said bracket, coil springs mounted on said guide bolts for placing said arcu-

ately curved shoe member under tension, and adjusting nuts threaded on said bolts for varying said tension, said shoe member being curved in a longitudinal direction and the other of said wing extensions being curved in a direction transverse to said longitudinal direction.

FRANCIS JOHNSON.
